UNITED STATES PATENT OFFICE.

JAMES LEONARD MOORE, OF WELLSVILLE, NEW YORK, ASSIGNOR TO THE MOORE STEAM TURBINE CORPORATION, OF WELLSVILLE, NEW YORK, A CORPORATION OF NEW YORK.

TURBINE BLEEDER VALVE.

Application filed March 16, 1922. Serial No. 544,148.

To all whom it may concern:

Be it known that I, JAMES LEONARD MOORE, a citizen of the United States, residing at Wellsville, in the county of Allegany and State of New York, have invented certain new and useful Improvements in Turbine Bleeder Valves, of which the following is a full and clear description thereof.

10 This invention relates to bleeder valves as applied to turbines, and more particularly designed and adapted for use in connection with high pressure condensing steam turbines.

15 The objects of the invention are:—

First, to construct and arrange a steam turbine bleeder valve which is supported in two end bearings having a small clearance with the valve stems supporting said valve 20 and the main body of the valve will have a slightly greater clearance in its seat or bored section of the turbine casing, so that the entire weight of the valve will be taken up or carried by said end bearings and not 25 on the larger section or main body of the valve, thereby greatly reducing the friction between the valve and its seat and hence permitting easy and quick operation of the valve under all conditions of service which 30 the turbine might be subjected to.

Second, to construct a bleeder valve particularly adapted for use in connection with a steam turbine, which will not stick or rust in the turbine casing while remaining in one 35 position during the summer months when steam is not being bled or used in the heating or other auxiliary systems, and hence avoid a common and troublesome defect in bleeder valves now in common use in which no 40 clearance is provided between the valve and the bored section of the turbine casing.

Third, to construct a bleeder valve for 45 use in connection with high pressure condensing turbines having a small clearance between the outside diameters of the valve and the turbine casing bored to receive said 50 valve, so that said valve in its closed position is not absolutely steam-tight, whereby a small volume of steam is capable at all times to pass through the final stages of the turbine to the condenser for the purpose of preventing said final stages from becoming overheated.

Fourth, to construct the shape of the bleeder valve and arrange or locate the same 55 in the turbine casing, so that a large and unrestricted area or outlet for the passage of the steam from the first to final stages can be provided for or effected, thereby insuring a minimum drop in steam pressure 60 between said stages and providing a high efficiency of operation during the summer months when no steam is bled from the turbine.

Other objects and advantages of the invention will appear from the detailed disclosure of the construction and arrangement 65 of elements and mode of operation to be presently described.

The invention consists of structural characteristics and relative arrangements of elements which will be hereinafter more fully described and particularly pointed out in the appended claims.

In the two sheets of drawings, in which 75 similar reference characters indicate the same parts in the several figures:

Figure 1 is a longitudinal vertical section of a portion of a turbine provided with the improved bleeder valve, and taken on the 80 line I—I of Figure 2.

Figure 2 is a transverse vertical section, taken on line II—II of Figure 1, and

Figure 3 is a fragmentary sectional view, taken on line III—III of Figure 2, when 85 the valve is open.

In the drawings, 10 is the turbine casing which is provided with a live steam or high pressure inlet 11 and a low pressure outlet 12. Within the turbine casing 10 and interposed between the said live steam or high pressure inlet 11 and the low pressure outlet 12 is provided a diaphragm 13, which separates two stages of expansion of the multi-stage turbine, said chamber 14 in the instance illustrated in the drawing being the first or high pressure stage, while chamber 15 is the second or a lower pressure stage. The first stage or high pressure chamber 14 is provided with an opening 141 or bleeder 90 connection, which is adapted to be in communication with the heating system, or other auxiliary device of the plant.

In each of said chambers 14 and 15 are respectively stator members 16 and 17 and 100 rotor members 18 and 19, said rotor mem-

bers 18 and 19 being fixed to a rotary shaft 20 supported in suitable fluid-tight bearings 21 within the front and rear heads of the casing 10 as is common in this class of engines and forms no part of the present invention.

The casing 10 or cylinder of the turbine at the section corresponding preferably at the upper edge of the diaphragm 13 is so formed and constructed as to provide an opening or passageway 22 which forms a communication between the first or high pressure stage chamber 14 and the second or lower pressure stage 15. The cylinder or casing 10 and the upper edge of the diaphragm 13 are bored transversely to the longitudinal axis of the turbine in such a manner as to form jointly a circular valve seat 23 in which is disposed or arranged the bleeder valve 24. Said bleeder valve 24 is supported and carried by two stub valve stems or spindles 25 and 26, which stems rest in bearings 27, 27, as shown, on either side of the turbine casing 10, and said valve stems 25 and 26 are so proportioned with respect to their bearings 27, and arranged with regard to the body of the bleeder valve 24 that said stems or spindles 25 and 26 carry the full weight of said valve 24 and the clearance of the stems 25 and 26 in their bearings is such that said valve 24 may be easily turned by a governor, not shown, and illustrated for example in U. S. Patent No. 801,322 to Kerr dated October 10, 1905, which may be attached or linked to a lever or arm 28 on the outer end of the stem 26, as indicated in Figure 2, and common in this class of inventions and needs no further disclosure.

The main body of said bleeder valve 24 is formed with a diametrical partition 29 and a connected circular section 30, so constructed and arranged that when the valve 24 is turned into the position shown in Figure 3, the two chambers 14 and 15 on the opposite sides of the diaphragm 13 are in communication with each other through the passageway or opening 22, permitting the high expanded steam to pass from the first stage to the succeeding stages of expansion and to the final exhaust opening and thence to the condenser, not shown.

The main body of the valve 24 is of such a diameter that a degree of clearance is provided between the main body of the valve 24 and its outer seat 23, so that said valve 24 does not rest on its seat but is supported, as previously described, entirely by the stems or spindles 25 and 26 and will accordingly permit a small clearance or restricted passageway 31 to be formed at the upper edge of the diaphragm 13, as indicated in Figure 1, through which a slight leakage of steam from the chamber 14 to chamber 15

can take place when the bleeder valve 24 is closed, as shown in Figure 1. This arrangement and construction of valve 24 with respect to its seat will not only enable a small quantity of steam to pass at all times through the final stages of the turbine to the condenser when the valve 24 is closed, and thereby preventing these final stages from becoming overheated as when running dry or without expanded steam as in prior turbines provided with bleeder valves, but at the same time insures the easy turning and operation of the valve at all times and eliminates all danger of the bleeder valve 24 sticking or rusting to its seat during the summer months when the bleeder valve 24 is open, as shown in Figure 3 and no expanded steam is used in connection with the heating system, or for other auxiliary use or apparatus of the plant.

It will also be seen by the shape and configuration of the valve 24 and its arrangement with respect to the diaphragm 13 and casing 10, a large undivided or unrestricted cross-sectional area or aperture forming passageway or opening 22 can be opened up between the two chambers 14 and 15, thereby effecting a minimum reduction in pressure of the steam in passing from chambers 14 to 15 and hence greatly increase the efficiency of the turbine during the six or seven months when no steam is being bled.

From the foregoing description of the construction and arrangement of parts, mode of assembling the same and their operation, it will be seen that all the objects and advantages recited in the statement of invention have been fully, efficiently and cheaply carried out, and while the preferred form has been shown and described, it is to be understood that many changes will suggest themselves without in any way varying the essential features of construction or departing from the spirit of the invention as expressed in the claims.

What I claim is:—

1. A multi-stage expansion steam turbine comprising a casing having a live steam or high pressure inlet and final low pressure outlet, means for effecting a plurality of stages of expansion within said casing and interposed between said inlet and outlet, a diaphragm within the casing separating one stage of expansion from a succeeding stage of expansion and provided with an opening for the passage of the steam from one stage to the adjacent succeeding stage of expansion, an intermediate steam pressure outlet communicating with a stage ahead of the diaphragm and receiving expanded steam and exterior of the casing, a rotary cylindrical bleeder valve disposed in said opening and solely supported at its ends and having ports, arranged and adapted to con-

trol the passage of the expanded steam through said opening from one stage to a succeeding stage or into the intermediate fluid pressure outlet, said bleeder valve provided with a clearance between its seat and valve body whereby said valve will not rust or stick to its seat or turbine casing and also permit a small volume of expanded steam to constantly pass through said clearance to the other stages of expansion between said diaphragm and final low pressure outlet when said bleeder valve is in its closed position.

2. A multi-stage expansion steam turbine comprising a casing having a high pressure inlet and final low pressure outlet, means for effecting a plurality of stages of expansion within said casing and interposed between said inlet and outlet, a diaphragm 20 within the casing separating one stage of expansion from a succeeding stage of expansion and provided with a bleeder valve seat and an opening for the passage of the steam from one stage to the adjacent succeeding stage of expansion, an intermediate steam pressure outlet communicating with a stage ahead of the diaphragm and receiving expanded steam and exterior of the casing, a rotary cylindrical bleeder valve disposed 25 in said opening and supported solely at its ends and within said seat and having ports, arranged and adapted to control the passage of the expanded steam through said opening from one stage to a succeeding stage or into the intermediate fluid pressure outlet, said bleeder valve provided with a clearance between its cylindrical seat and valve body, whereby said valve will easily rotate and not rust or stick to its seat or turbine casing and also permit a small volume of expanded steam to constantly pass through said clearance the other stages of expansion between said diaphragm and final low pressure outlet when said bleeder valve is in its closed position.

3. A multi-stage expansion steam turbine comprising a casing having a live steam or high pressure inlet and final low pressure outlet, means for effecting a plurality of stages of expansion within said casing and interposed between said inlet and outlet, a diaphragm within the casing separating one stage of expansion from a succeeding stage of expansion and provided with an opening 50 for the passage of the steam from one stage to the adjacent succeeding stage of expansion, a cylindrical bleeder valve seat in the casing adjacent to said diaphragm, an intermediate steam pressure outlet communicating with a stage ahead of the diaphragm and receiving expanded steam and exterior of the casing, a rotary cylindrical bleeder valve solely supported at its ends and having ports, arranged and adapted to control the 55 passage of the expanded steam through said

opening from one stage to a succeeding stage or into the intermediate fluid pressure outlet, said bleeder valve provided with a cylindrical clearance extending the full length of the valve between said valve seat and valve body, whereby said valve will easily oscillate and not rust or stick to its seat or turbine casing and also permit a small volume of expanded steam to constantly pass through said clearance to the other stages of expansion between said diaphragm and final low pressure outlet when said bleeder valve is in its closed position.

4. A multi-stage expansion steam turbine comprising a casing having a live steam or high pressure inlet and final low pressure outlet, means for effecting a plurality of stages of expansion within said casing and interposed between said inlet and outlet, a diaphragm within the casing separating one stage of expansion from a succeeding stage of expansion and provided with an unrestricted opening for the passage of the steam from one stage to the adjacent succeeding stage of expansion, an intermediate steam pressure outlet communicating with a stage ahead of the diaphragm and receiving expanded steam and exterior of the casing, a rotary cylindrical bleeder valve solely supported at its ends and provided with ports, arranged and adapted to unobstructedly control the passage of the expanded steam through said opening from one stage to a succeeding stage or into the intermediate fluid pressure outlet, said bleeder valve provided with a clearance between its seat and body, whereby said valve will easily oscillate and not rust or stick to its seat or turbine casing and also permit a small volume of expanded steam to constantly pass through said clearance to the other stages of expansion between said diaphragm and final low pressure outlet when said bleeder valve is in its closed position.

5. A multi-stage expansion steam turbine comprising a casing having a live steam or high pressure inlet and final low pressure outlet, means for effecting a plurality of stages of expansion within said casing and interposed between said inlet and outlet, a diaphragm within the casing separating one stage of expansion from a succeeding stage of expansion and provided with an opening for the passage of the steam from one stage to the adjacent succeeding stage of expansion, a bleeder valve seat in the casing, an intermediate steam pressure outlet communicating with a stage ahead of the diaphragm and receiving expanded steam and exterior of the casing, a rotary cylindrical bleeder valve having a diametrical partition and a connected circular section forming ports, arranged and adapted to control the passage of the expanded steam through said opening from one stage to a succeeding

stage or into the intermediate fluid pressure outlet, said bleeder valve supported solely at its ends and unobstructedly of its seat and provided with a clearance between the seat and valve body whereby said valve will easily rotate and not rust or stick to its seat or turbine casing and also permit a small

volume of expanded steam to constantly pass through the other stages of expansion between said diaphragm and final low pressure outlet when said bleeder valve is in its closed position. ¹⁰

In testimony whereof I affix my signature.
JAMES LEONARD MOORE.
